ATTACHMENT BAR FOR TRAILER HITCH BALL BRACKET

William L. Rendessy, 8028 N. 14th Place,
Phoenix, Ariz. 85020

Filed July 24, 1973, Ser. No. 382,146

Term of patent 14 years

Int. Cl. D12—16

U.S. Cl. D12—162

FIG. 2

FIG. 1 is a top perspective view of an attachment bar for trailer hitch ball bracket showing my new design, it being understood that the broken line showing of the ball and ball bracket are for illustrative purposes only; and

FIG. 2 is a bottom perspective view thereof.

I claim:

The ornamental design for an attachment bar for trailer hitch ball bracket, as shown and described.
